Thomas Goodwin

Letter's Patent.

The Schedule referred to in these Letters Patent, and making part of the same, containing a description in the words of the said Thomas Goodwin himself of his improvement in the art of Manufacturing Neck Stockings.

This applicant uses whalebone in the making of Neck Stockings and of the cloth or body thereof instead of hair or bristles as is now and formerly used. The whalebone is to be prepared by being divided into small strips or slices about the size of hog bristles or larger or smaller as may be wished and then woven in and into the bottom or other warp of other materials thus making a kind of cloth of any convenient size, composed of the whalebone strips as filling or part and of bottom or liner or silk thread or any other material for the alternate threads of the filling and for the warp. This cloth is then to be shaped into stocks. To effect this the cloth is to be placed on a frame of the shape or nearly the ^{shape} of a person's neck and to be filled thereto by means of steaming or any other heat. The advantage of this material (whalebone) over other materials consists in its cheapness and in its preserving in a superior degree its elasticity, and nothing as liable as other materials to be broken down; and in its uniformity of size, being the same size throughout whereas bristles and hair are tapering, and larger at one end than at the other, after the stocks are formed they may be covered if desired with silk or any other material.

The principle of this improvement consists in the manufacture of Neck Stockings with strips or pieces of whalebone of any convenient size and shape instead of bristles or hair, substantially in the method above described.
